UNITED STATES PATENT OFFICE

168,694

GEOMETRICAL INSTRUMENT

Gustav Langer, Chula Vista, Calif., assignor to
Rohr Aircraft Corporation, Chula Vista, Calif.,
a corporation of California

Application October 8, 1952, Serial No. 21,764

Term of patent 14 years

(Cl. D52—1)

To all whom it may concern:

Be it known that I, Gustav Langer, a citizen of the United States, residing at Chula Vista, San Diego County, State of California, have invented a new, original, and ornamental Design for Geometrical Instrument of which the following is a specification, reference being had to the accompanying drawing, forming a part hereof.

Fig. 1 is a plan view of a geometrical instrument, showing my new design.

Fig. 2 is a top view of the instrument of Fig. 1 and,

Fig. 3 is an edge view of the instrument of Fig. 1.

I claim:

The ornamental design for a geometrical instrument, as shown.

GUSTAV LANGER.
